UNITED STATES PATENT OFFICE.

FOSTER C. NIXON, OF APOLLO, PENNSYLVANIA.

ELECTROLYTIC APPARATUS.

Application filed February 18, 1927. Serial No. 169,825.

This invention relates to an electrolytic apparatus, the general object of the invention being to provide means for supporting the plates to be treated in a vertical position while they are being passed through the electrolytic tank, with means for making the electrical connection at the upper edges of the plates while their lower edges are engaging grooved power pulleys which give the plates their movement.

Another object of the invention is to provide insulated rods at the top of the tank and extending longitudinally thereof for supporting the anode plates which are provided with hooks at their upper edges for this purpose, the rods being connected to the circuit.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view of the apparatus. Figure 2 is a section on line 2—2 of Figure 1.

Figure 3 is a section on line 3—3 of Figure 1.

In these views, 1 indicates the tank for containing the electrolytic bath and 2 indicates the anode plates which are suspended by their hooks 3 from the rods 4 which are supported by the blocks 5 of insulating material attached to the upper edges of the ends of the tank. A plurality of grooved pulleys 6 arranged adjacent the bottom of the tank, each pulley being carried by a shaft 7 which is journaled in the tank and has one end passing through one side thereof, this projecting end receiving the pulley 8 over which the rubber belts 9 pass so that the shafts can be rotated from a suitable source of power. These grooved pulleys engage the lower

edges of the plates A to be treated and these plates are supported in vertical position in the tank by means of the rollers 10, each pair of which is carried by a vertically arranged shaft 11 supported by the brackets 12 which are fastened to the interior side walls of the tank. These shafts are arranged in pairs,

with one shaft of each pair directly opposite the other shaft of the pair, with the rollers of the two shafts spaced apart a distance equal to the thickness of the plate to be treated so that the rollers will engage the two faces of the plate and thus support the same in vertical position.

The rollers 10 on one pair of shafts are differently situated from the rollers on another pair of shafts so that the rollers will not contact with the same parts of a plate, which would cause the rollers to interfere with the depositing of the material thereon.

The upper edges of the plates are engaged by a grooved pulley 13 which is carried by a hanger 14 which is insulated from a support 15 attached to an upright 16 on the tank by a hinge 17 so that the support, the hanger and the pulley can be moved from over the tank in order to remove a plate from the tank or place a plate in the tank. A conductor 18 is connected with the hanger 14 and conductors 19 are connected with the rods 4, these conductors being connected with a source of supply so that current will be supplied to the anode plates and the plates being treated in the usual manner.

From the foregoing, it will be seen that the plates A being treated will be moved through the tank when the shafts 7 are being rotated in a vertical position and parallel to the anode plates 2 so that said plates will be thoroughly covered with electrolytic material. By having the plates stand on edge, the scale will fall off the plates so that a product will be produced which will have less defects than where the plate is placed on its side. By having the current supplied to the plate through the grooved pulley 13, the current is automatically broken as soon as the plate passes the pulley.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

An electrolytic apparatus for treating plates comprising a tank, a pair of rods extending longitudinally across the top of the tank and insulated therefrom, anode plates, hooks at the upper edges thereof for engaging the rods so that the plates will be sus-

pended in the tank, a plurality of shafts journaled in the lower part of the tank, a grooved roller on each shaft for engaging the lower edges of the plates to be treated, means for rotating the shafts, vertically arranged shafts in the tank arranged in pairs, a pair of rollers on each shaft for engaging the faces of the plates to be treated, the rollers on one pair of shafts being staggered 10 with relation to the rollers on another pair

of shafts, a grooved roller for engaging the upper edges of the plates to be treated, means for supporting the same, means for connecting said roller and the rods to a source of supply and an arm hinged to a 15 part of the tank and carrying the supporting means for the last mentioned roller.

In testimony whereof I affix my signature.

FOSTER C. NIXON.
